Inventor;

B. S. Morgan

UNITED STATES PATENT OFFICE.

BEVEL S. MORGAN, OF DELHI, IOWA.

IMPROVED CLOTHES-POUNDER.

Specification forming part of Letters Patent No. **75,562**, dated March 17, 1868.

To all whom it may concern:

Be it known that I, BEVEL S. MORGAN, of Delhi, in the county of Delaware and State of Iowa, have invented a new and useful Implement for Pounding and Lifting Clothes; and I do hereby declare that the following is a full, clear, and exact description of the construction and operation of the same, reference being had to the annexed drawings, making a part of this specification, in which—

The shaded figure represents the implement or device with the handles and head or jaws closed when used for pounding, and the figure described by dotted lines represents the handles and jaws of the head extended preparatory to seizing the clothes for the purpose of lifting them or moving them about.

Said device is constructed of two pieces of wood, each hollowed out on one side of the head, (letters C C,) leaving a projection at the extreme end of the head, (letters B B,) forming a cavity in the head where the jaws are closed, (letter C shaded figure,) the two pieces joined together by an iron or wood pin near the head, (letter A,) and being smaller above, where they are joined at letter A, the two forming a handle, when closed together, for pounding, and

forming two handles, (when extended,) letters E E. It is used for pounding clothes in a vessel, for seizing the clothes by opening and closing the sections of the head D D for the purpose of turning or moving them about, and also for lifting clothes out of the vessel. It is operated entirely, both in the pounding and in the seizing of the clothes and moving them about, by the handles E E, the opening of the handles, as in figure described by the dotted lines, operating to open the two sections of the head, as shown in the same figure, and the closing of the handles in shaded figure operating to close the two sections of the head, as shown in the shaded figure.

What I claim as my invention, and desire to secure by Letters Patent, is—

The construction of the two pieces of wood D D and E E, the hollowed surface of each of the two sections of the head C C forming the cavity C when closed, as and for the purpose specified.

BEVEL S. MORGAN.
